UNITED STATES PATENT OFFICE.

PETER R. GONSKY, OF CHICAGO, ILLINOIS.

CONTAINER FOR NEW AND DISCARDED ARTICLES.

1,379,098.

Specification of Letters Patent.

Patented May 24, 1921.

Application filed March 3, 1920. Serial No. 362,949.

To all whom it may concern:

Be it known that I, PETER R. GONSKY, a subject of the King of England, residing at Chicago, in the county of Cook and State 5 of Illinois, have invented certain new and useful Improvements in Containers for New and Discarded Articles, of which the following is a specification.

The invention has for an object to effect 10 improvements in receptacles or containers of new and discarded articles, such as the points or needles for use upon gramophones and graphophones and particularly aims to economize the use of materials and space in 15 providing such an appliance. It is a particular aim to enable the space ordinarily occupied by one receptacle for needles to be used both for holding new needles, and for receiving and concealing used needles in 20 such manner that the two may not become mixed or the used needles obtained except by volition. It is also an aim to make it possible to dispose of used needles at a 25 point convenient to the container of new needles, so that a minimum of delay or annoyance will be involved in putting used needles in a separate receptacle from that in which the new needles are contained.

It is also an aim of the invention to enable 30 the economical production of an appliance for attaining the ends in view; as well as to enable the ready manipulation of the device for cleaning or emptying.

The invention involves also additional objects, advantages, and features of invention, 35 in the structural form, relation and combination of parts hereinafter set forth and shown in the drawings, wherein,

Figure 1 is a fragmentary view of a stand 40 device upon which one embodiment of my invention is incorporated,

Fig. 2 is a detail sectional view of the combined container,

Fig. 3 is a top view thereof,

Fig. 4 is a bottom view of the upper member.

Fig. 5 is a view partly in section showing the adaptability of the device to use in table elements or top portions of cabinets, and 50 like situations.

Fig. 6 is an enlarged view of the coengaged edge portions of the upper and lower members of the device.

There is illustrated a combined receptacle 55 or container for new and used phonographic needles or the like, comprising a

bottom receptacle member or cup 10 which has heretofore been produced by stamping a disk of suitable metal to the desired form between properly shaped dies, the receptacle 60 being circular in form and having its edge portion formed in the usual manner with a rolled rim, which I subsequently further work by a spinning operation so as to press the outer part downwardly and form a 65 frusto-conical surface 13, forming an acute angle with the inner wall surface 14 of the cup. When made for use for holding phonograph needles, the bottom member 10 has been made one inch and a half in diameter, 70 and about $\frac{7}{8}$ (seven-eighths) of an inch deep, its bottom portion being nearly or quite flat in some cases, although this may be varied if desired.

Removably engaged upon the bottom 75 member 10 there is a top and receptacle element 15, similar in shape in its body part, but smaller in diameter and in depth, the receptacle part proper being ordinarily formed one and one-eighth inches in diameter and one-half an inch in depth. It is provided with a planiform horizontal flange portion 16, circumscribing the receptacle, and having a down-turned outer edge portion or flange 17 adapted to fit loosely over 80 the larger part of the rim 12, and to extend a short distance below this rim as shown in Fig. 6. At one or more places, the flange portion 17 is slightly crimped or indented on its lower edge portion, as shown at 18 in 85 Fig. 6, so that the immediately adjacent part of the flange inclines inwardly toward its lower edge, and is adapted to engage resiliently under the rim 12 to yieldably resist separation of the two parts of the device when assembled. Arcuate slots 19 concentric with the vertical axis of the device are formed in the top flange 16, so as to fall over the annular space 20 between the walls of the two members when coengaged properly.

The top member is adapted to be pressed upon the bottom member so that the crimp 18 will slide upon the inclined surface 13 springing the metal so that the crimp may 105 engage under the rolled edge 12 when the parts have been pressed into snug engagement. The parts may also be separated manually by a slight application of force.

In the use of the device, it may be set in 110 a circular well or opening in a table piece 21, one or more of the combined devices

being located side by side or in a series, as shown in Fig. 5. I have also mounted the device in a swinging wire bracket as illustrated at 22 in Fig. 1, so mounted that it may swing under a leg or other part of an article, the outer end of the arm being bent to form a hook or eye adapted to snugly engage around the lower receptacle 10, and so hold it that it may be readily lifted from the arm when desired. Or, the supporting bracket may be permanently fixed in the lower receptacle 10 as indicated at 22' in Fig. 2.

What is claimed:

15 As an improved article of manufacture, a

sheet metal cover element for phonograph needle cups, the cover having a peripheral down-turned flange to fit around a cup and having a receptacle part pressed centrally therein, and being formed also with a needle receiving slot therethrough immediately without and adjacent the receptacle part for the purposes described.

In testimony whereof I have affixed my signature in presence of two witnesses.

PETER R. GONSKY

Witnesses:

I. WASKEWIZ,
E. VAN EPPS.
